(57) CLAIM

I claim the ornamental design for the “sun lounger,” as shown and described.

DESCRIPTION

FIG. 1 is a front perspective view of the sun lounger of the present invention;

FIG. 2 is a view from a first side;

FIG. 3 is a front view thereof;

FIG. 4 is a rear view thereof;

FIG. 5 is a top plan view thereof;

FIG. 6 is a bottom plan view thereof;

FIG. 7 is a rear perspective view thereof;

FIG. 8 is a view from a second side; and,

FIG. 9 is a front perspective view of the sun lounger in a closed position.
